FLUID PUMP

John C. Fisher, 45 Sparks St., Cambridge, Mass.

Filed Oct. 24, 1956, Ser. No. 617,993

7 Claims. (Cl. 103—76)

This invention relates to an improved pump particularly suitable for use in transmitting corrosive fluids, toxic or inflammable fluids, fluids containing abrasive materials in suspension, and other fluids which cannot be satisfactorily handled by conventional pumps.

Displacement, rotary and centrifugal type pumps not only embody one or more impellers and other moving parts with which the liquid being pumped comes in contact, but also a power-transmitting element driven from an external source. When such pumps are used to transmit corrosive liquids, solvents, etc. the moving parts and other surfaces coming in contact with the liquid must either be made from a relatively costly, corrosive-resistant material, or they must be provided with a protective coating which after a relatively short period of use is apt to wear or become stripped, thus introducing contamination into the liquid being pumped. Moreover, since such pumps are driven from an external source it is necessary to use packing glands or the like seals which must be periodically replaced in order to guard against leakage. Consequently both the initial and maintenance costs of such pumps are relatively high.

The principal objects of the present invention are to provide a pump which has completely sealed fluid carrying members so that no leakage is possible, such as might occur with conventional centrifugal, vane, piston or rotary pumps; and to provide a simple, effective and reliable pump capable of handling molten materials under relatively high pressure, such for example as sodium at a temperature of 400° C. and a pressure exceeding 1,000 p.s.i.

Other objects are to provide a pump capable of handling a fluid containing solid or abrasive particles, such as encountered in a coolant system for machine tools, to provide a pump which can safely handle toxic materials such as radio-active substances and highly inflammable or explosive fluids, etc., where leakage must be avoided, and to provide a pump the output of which may be varied without using a valve or the like.

Further objects will be apparent from a consideration of the following description and the accompanying drawings, wherein:

Fig. 1 is an elevation, with parts broken away and shown in section, of a simplified embodiment of my invention;

Fig. 2 is a section on the line 2—2 of Fig. 1;

Fig. 3 is an axial section through one of the fluid barriers;

Fig. 4 is a schematic view of one of the fluid rectifiers;

Fig. 5 is an elevation, with parts broken away and shown in section, of another form of the invention embodying polyphase fluid rectification;

Fig. 6 is an elevation of the system as viewed from the line 6—6 of Fig. 5;

Fig. 7 is an elevation of the system as used from the line 7—7 of Fig. 5;

Fig. 8 is a section on the line 8—8 of Fig. 5; and

2

Fig. 9 is a longitudinal section through one of the fluid rectifiers.

The principles underlying the present invention are substantially the same as those set forth in my copending applications Serial Nos. 553,015 and 578,777, filed December 14, 1955, and April 17, 1956, respectively, in that one or more elongate enclosure or tubes having radially non-expandable walls, i.e., walls which are non-expandable in a direction perpendicular to the longitudinal axes and containing a propellant fluid is oscillated so as to produce an alternating fluid flow which acts on a fluid in an associated circuit through the intermediary of a fluid rectifier so as to induce a unidirectional flow in the associated circuit. Where the propellant fluid and the fluid being pumped should not come in contact, a fluid barrier is interposed between the enclosure and fluid rectifiers. Such a fluid barrier comprises a pair of chambers separated by an impervious flexible wall or diaphragm operative to transmit pressure surges from one chamber to another, and one of these chambers is connected with the enclosure and the other is connected with the inlet of the fluid rectifier so that a unidirectional flow through the discharge port of the rectifier takes place in response to an alternating flow in the enclosure and chamber connected therewith.

The various parts of the system may be made from any suitable corrosion-resistant metal, or a chemically inert material such as a polyamide (nylon), polyethylene, a halogenated polyethylene (Teflon), polyvinylidene chloride (Saran), an acrylic acid resin or ester, a suitable polyester or an epoxy resin, provided they possess the desired degree of rigidity, strength and fatigue resistance. In any case the particular material selected will depend upon the type of fluid on or with which the pump is to operate, the temperature of the fluid, etc., and these same considerations are applicable to the external or associated circuit and parts connected therewith. The means for oscillating the enclosures may be mechanical or electrical, the latter type being preferred since it is subject to better control.

Referring to Figs. 1 to 4, the embodiment shown therein comprises an elongate base having an upright back or wall 2, the base 1 supporting an electrodynamic vibrator 4 which acts on an elongate enclosure 5 having flexible sections 6 at each end, and the wall 2 supports a pair of fluid barriers 8 (Fig. 3) and a fluid rectifier 10 (Fig. 4). The enclosure 5 may consist of a length of stainless steel tubing or other suitable material, as above pointed out, but where, as here shown, a single length of tubing is employed, its opposite ends are coiled to provide the flexible sections 6 which permit the tube 5 to oscillate axially.

The electrodynamic vibrator 4 comprises a fixed core 12 suitably anchored to the base 1 and formed with a central opening 14 through which the tube 5 passes with adequate clearance and an annular recess which receives a field coil 15 which may be connected to any suitable source of direct current so as to produce a high flux concentration in the core 12. Integral with the core is a central projection 16 which loosely fits about the tube 5 and firmly secured to the tube 5 in close proximity to the outer end of the projection 16 is an armature 18 having three radial arms 20, each formed with an opening through which extends a guide stud 21. The inner ends of these guide studs are threaded into a closure plate 24, and the outer ends of the studs are suitably clamped to an upstanding bracket 25 secured to the base 1, the bracket 25 being formed with an opening through which the tube 5 passes with adequate clearance.

The inner face of armature 18 is formed with a circular projection 26 to which a sleeve 28 is firmly secured and an armature coil 30 is wound about the sleeve 28 so

as to cause the armature and tube to oscillate in response to the passage of an alternating current therethrough. A coil compression spring 32 acts against the closure plate 24 and the inner face of the armature 18, and a second spring 34 acts against the outer face of the armature 18 and the bracket 25. These springs 32 and 34 not only normally hold the armature 18 in a central or neutral position when the parts are at rest, but they are selected so that their stiffness and characteristics produce a natural frequency of oscillation of the mass which is at least approximately the same as the frequency of the alternating armature coil current. Hence, the force produced by the armature coil 30 is used only to overcome the net resistance of the tube 5 and associated parts, and the opposition of the propellant fluid to flow back and forth through the tube 5, coils 6 and fluid barrier 8.

Upper ends of the coils 6 are integral with inwardly directed extensions 35 which are rigidly secured to the wall 2 by clamps 36. The coils 6 thus provide flexible sections which support the opposite ends of the tube 5 so that the tube may be oscillated by the vibrator 4. The ends of the extensions 35 are connected with fluid barriers 8 each of which comprise a cylindrical outer chamber 38 within which is a bellows 40, the open end of which is connected to one of the extensions 35, through an opening in one end of the chamber 38. The opposite end of the chamber 38 is formed with an outlet opening 42 which is connected by a duct 44 with the fluid rectifier 10.

Within the internal circuit or enclosure defined by the tube 5, coils 6, extensions 35 and bellows 40, is a propellant fluid such as mercury or the like relatively heavy liquid, and within that part of the external circuit comprising the chamber 38 and ducts 44 is the fluid to be pumped. Oscillations imparted to the tube 5 by the vibrator 4 create an alternating flow in the internal circuit which is transmitted through the bellows 40 to the fluid in the chamber 38 and ducts 44, as indicated by the arrows in Fig. 4.

The fluid rectifier 10, here shown schematically, may be of the same construction as that shown in my aforementioned copending applications, but in any case is provided with inlet passages 50 and 51 which are connected with the ducts 44. These inlet passages are provided with branches 52, 53, 54 and 55 having check valves 56, 57, 58 and 59 or the like means permitting fluid flow into the branches 52 and 54 and out through the branches 53 and 55, but opposing fluid flow in the opposite directions. The branches 52 and 54 are interconnected by a duct 60 and the branches 53 and 55 are likewise interconnected by duct 62. An intake line 64 is connected with the duct 60 and a discharge line 66 is connected to the duct 62. Hence, an alternating fluid flow in the inlet ducts 44 creates a pulsating fluid flow inwardly through intake line 64 and outwardly through discharge line 66, and during this process the check valves 56 and 59 are opened simultaneously while check valves 57 and 58 are closed when the internal flow is from passage 50 to passage 51, but when the internal flow is from passage 51 to passage 50 check valves 57 and 58 are opened and check valves 56 and 59 are closed.

In operation the internal circuit is completely filled with a propellant fluid such as mercury so as to be free from gas pockets and the field coil 15 is connected with a suitable source of direct current. The armature coil 30 is connected through a control switch (not shown) with a source of alternating current so that upon closing the switch the tube 5 is oscillated at the same frequency as that of the alternating current. By varying the frequency and/or amplitude of the alternating current, the frequency of oscillation of the tube 5 and the acceleration imparted to the fluid therein may be varied. If, for example, a 60 cycle frequency is used the tube 5 oscillates 60 times per second, and due to the acceleration imparted to the fluid therein there will be 60 pressure surges per

second acting on the fluid within each chamber 38 and as a result there will be 120 pressure surges per second forcing liquid out through the discharge line 66 and the same number of surges drawing fluid in through the intake 64.

The alternating fluid flow in the internal circuit thus acts through the bellows 40 to create a unidirectional pulsating flow in the discharge line 66 without either fluid coming in direct contact. Hence, it is possible to pump fluids through the external circuit which would seriously react with the propellant fluid of the internal circuit. If desired, the unidirectional pulsating flow in the external circuit may be "smoothed out" by interposing between the intake and discharge lines 64 and 66 a smoothing device such as disclosed in my copending application Serial No. 578,777, filed April 17, 1956.

The embodiment shown in Figs. 5 to 9 is, in principle, the same as that of Figs. 1 to 4, but it is designed for three phase operation. The particular pump shown comprises an elongate base 71, such as a length of channel iron, having at opposite ends upstanding walls 72 and 74. Extending between the walls 72 and 74 are three parallel elongate enclosures or accelerator tubes 80, 81 and 82, preferably of stainless steel or the like material, having their axes lying in a common circle and spaced 120° apart. The opposite ends of the tubes are coiled to provide flexible sections 80a, 80b, 81a, 81b and 82a, 82b. Three aligned electrodynamic vibrators 84, 85 and 86, one for each tube, are mounted in spaced relation on the base 71 between the coiled ends of the tubes. The outer ends of the coils 80a, 81a and 82a are interconnected as hereinafter described and the outer ends of coils 80b, 81b and 82b are connected with fluid barriers 90, 91 and 92 which in turn are connected with fluid rectifiers 94, 95 and 96 having interconnected intakes and discharge ports 35 hereinafter more fully described.

The electrodynamic vibrators are substantially identical, each comprising a back plate 100 and an annular outer pole piece or front plate 101, both bolted to a spacer ring 102 having foot brackets 103 bolted to the base 71. A conical-shaped permanent magnet 104, preferably of high coercive force (Alnico), is secured to the back plate 100 and the reduced end of this magnet carries an inner pole piece 106 spaced from the inner periphery of the outer pole piece so as to define an annular gap 108 which carries a radially directed, constant-density magnetic field. The back plates 100, magnets 104 and inner pole pieces 106 are each provided with three aligned clearance openings through which the tubes 80, 81 and 82 extend, the openings in the back plates and inner pole pieces being appropriately bushed so as slidably to support the intermediate portions of the tubes.

A circular flanged plate 110, preferably of aluminum alloy, is secured to each of the accelerator tubes and each plate is formed with two clearance openings through which the other accelerator tubes pass so as to permit them to be freely oscillated. One of these plates is normally disposed midway between the adjacent inner pole piece of vibrator 84 and back plate of vibrator 85, the second between the pole piece of vibrator 85 and back plate of vibrator 86 and the third plate is disposed midway between the inner pole piece of vibrator 86 and the inwardly directed flange 111 of a cylindrical housing 112 (Fig. 5) which is bolted to the outer pole piece 101. Each flange plate 110 carries a thin tube or sleeve 114, preferably of stainless steel, which is concentric with the inner pole piece 106 and the free end portion of this tube projects into the gap 108. A solenoidal coil of wire 115 is carried by the free end of the sleeve 114 and reacts with a substantially identical coil 116 wound about the pole piece 106 in the opposite direction.

The coil 116 carries the same alternating current as the coil 115 and its purpose is to counteract the alternating magnetic field produced by the coil 115. The coils 115 and 116 are connected in delta or Y in a three phase

system, and any suitable means for ventilating the armature and compensating coils may be provided, a conventional forced air cooling system (not shown) usually being adequate.

A pair of opposed helical coils 120 and 121, acting against each of the flanged plates 110, is provided and the inherent stiffness of these coils is designed for such a value as to tune the moving mass of the accelerator tube (not including the propellant fluid inside it) to mechanical resonance at the frequency of the alternation of the armature currents. This also helps to improve the power factor of the armature winding and greatly reduces the necessary force rating of the armature coil.

The corresponding ends of the coils 80a, 81a and 82a are interconnected by fittings including a T 122, as shown in Fig. 6, and the coils 80b, 81b and 82b are connected with the fluid barriers 90, 91 and 92, respectively, as shown in Fig. 7. Each of these barriers is identical to the fluid valve 8, shown in Fig. 3 and heretofore described, and the outlet ducts 124, 125 and 126 of these barriers are connected to the fluid rectifiers 94, 95 and 96, respectively, each of which has the same construction.

As shown in Fig. 9, each rectifier comprises a T 128 having its intermediate branch 130 connected with an outlet duct of the associated fluid barrier and its other branches are connected with tubes 131 and 132 having Venturi passages 133 and 134 provided with ball checks 135, 136 and retainer pins 137, 138. The corresponding ends of the tubes 131 are connected with a header or collecting chamber 140 having an intake 141, and the ends 132 are connected with a header 142 having a discharge 144, the design being such that the ball checks oppose flow outwardly through the intake and inwardly through the discharge.

In operation the internal circuit, comprising the accelerator tubes 80, 81 and 82, their associated coils and interconnected ducts, and the enclosures defined by the bellows within the fluid barriers, is completely filled with a propellant fluid such as mercury or other liquid having a relatively high specific gravity. The external circuit, comprising the lines connected with the intake 141, discharge 144, the fluid rectifiers 94, 95 and 96 and parts connected therewith, contain the fluid to be pumped which may be any of the aforementioned substances, including molten sodium.

Where mercury is used as a propellant fluid with a three-phase sixty cycle alternating current, pressures of the order of 2,000 pounds per square inch may be built up in the external circuit. As a practical matter the output of a pump constructed in the manner above-described will depend upon the operating frequency and size of the accelerator tubes. As a general rule, frequencies of the order of 5 cycles per second constitute the lower practical limit and frequencies of the order of 100 cycles per second constitute the upper limit. Low frequencies require large tube displacements to obtain the required pressure and flow, whereas at higher frequencies the necessary amplitudes are reduced.

While I have shown and described different desired embodiments of the invention, it is to be understood that this disclosure is for the purpose of illustration and various changes and modifications may be made without departing from the spirit and scope of the invention as set forth in the appended claims.

I claim:

1. A fluid pump comprising an elongate tube having a radially non-expansible wall, the opposite ends of said tube terminating in coiled sections, a propellant fluid in said tube and coiled sections, manually controllable means for oscillating said tube at a uniform frequency and in opposite directions along its longitudinal axis so as to produce an alternating fluid flow therein, and a fluid rectifier having an intake port, a discharge port, valve means for opposing fluid flow outwardly through said intake port and inwardly through said discharge

port, and inlets between said valve means connected with said coiled sections that a unidirectional fluid flow through said discharge port takes place in response to alternating fluid flow in said tube and coiled sections.

5 2. A fluid pump comprising an elongate enclosure having a radially non-expansible wall, means defining two pairs of chambers, a flexible impervious wall separating said chambers and operative to transmit pressure surges from one chamber to the other, elongate flexible sections having radially non-expansible walls connecting the end portions of said enclosure with corresponding chambers, a propellant fluid in said enclosure, flexible sections and chambers connected therewith, means for oscillating said enclosure so as to produce an alternating fluid flow therein, and a fluid rectifier having an intake port, a discharge port, and means connecting the intake and discharge ports to the other chambers including means opposing fluid flow outwardly through said intake port and inwardly through said discharge port so as to produce a unidirectional fluid flow through said discharge port in response to alternating fluid flow in said enclosure, flexible sections and chambers connected therewith.

15 3. A fluid pump comprising an elongate tube having a radially non-expansible wall, means defining two pairs of chambers, a flexible impervious wall separating said chambers and operative to transmit pressure surges from one chamber to the other, flexible sections having radially non-expansible walls connecting the end portions of said tube with corresponding chambers, a propellant fluid in said tube, flexible sections and chambers connected therewith, means for oscillating said tube so as to produce an alternating fluid flow therein, and a fluid rectifier having an intake port, a discharge port, check 25 valves opposing fluid flow outwardly through said intake port and inwardly through said discharge port, and inlets between said check valves connected with the other chambers so as to produce a unidirectional fluid flow through said discharge port in response to alternating 30 fluid flow in said tube, flexible sections and chambers connected therewith.

35 4. A fluid pump comprising a plurality of elongate enclosures having radially non-expansible walls, means defining a plurality of pairs of chambers, a flexible impervious wall separating each pair of chambers and operative to transmit pressure surges from one chamber to the other, flexible sections having radially non-expansible walls connecting the end portions of said enclosures with corresponding chambers, a propellant fluid 40 in said enclosures, flexible sections and chambers connected therewith, means for oscillating said enclosures so as to produce an alternating fluid flow therein, and a fluid rectifier having an intake port, a discharge port, and means connecting the intake and discharge ports to the other chambers including means opposing fluid flow 45 outwardly through said intake port and inwardly through said discharge port so as to produce a unidirectional fluid flow through said discharge port in response to an alternating fluid flow in said enclosures, flexible sections and chambers connected therewith.

50 5. A fluid pump as set forth in claim 4, wherein there are three enclosures which are oscillated simultaneously 120° out of phase.

55 6. A fluid pump comprising a plurality of elongate tubes having radially non-expansible walls, means defining a plurality of pairs of chambers, a flexible impervious wall separating each pair of chambers and operative to transmit pressure surges from one chamber to the other, flexible sections having radially non-expansible walls connecting the end portions of said tubes with corresponding chambers, a propellant fluid in said tubes, flexible sections and chambers connected therewith, means for oscillating said tubes so as to produce an alternating fluid flow therein, and a fluid rectifier having an intake port, a discharge port, check valves oppos-

ing fluid flow outwardly through said intake port and inwardly through said discharge port, and a plurality of inlets between said check valves connected with the other chambers so as to produce a unidirectional fluid flow through said discharge port in response to an alternating fluid flow in said tubes, flexible sections and chambers connected therewith.

7. A fluid pump as set forth in claim 6, wherein there are three tubes disposed in parallel relationship, which tubes are oscillated simultaneously 120° out of phase.
